UNITED STATES PATENT OFFICE.

MAURICE L. NOVACK, OF MINNEAPOLIS, MINNESOTA.

DESIGN FOR A FINGER RING.

Application filed March 28, 1929. Serial No. 30,654. Term of patent 7 years.

To all whom it may concern:

Be it known that I, MAURICE L. NOVACK, a citizen of the United States, residing at Minneapolis, in the county of Hennepin and State of Minnesota, have invented a new, original, and ornamental Design for Finger Ring, of which the following is a specification, reference being had to the accompanying drawing, forming part thereof.

Fig. 1 is a plan or edge elevation of a section of the ring, showing my new design.

Fig. 2 is a side elevation of the ring portion shown in Fig. 1.

Fig. 3 is a sectional detail view on the line 3—3 in Fig. 2.

I claim:

The ornamental design for a finger ring as shown.

Signed at Minneapolis, Minnesota, this 25th day of March 1929.

MAURICE L. NOVACK.
